UNITED STATES PATENT OFFICE.

SAMUEL BERNSTEIN, OF CHICAGO, ILLINOIS, ASSIGNOR TO THE INSTANTANEOUS WATER HEATING COMPANY, OF SAME PLACE.

WATER-HEATER.

SPECIFICATION forming part of Letters Patent No. 429,300, dated June 3, 1890.

Application filed October 15, 1889. Serial No. 327,059. (No model.)

To all whom it may concern:

Be it known that I, SAMUEL BERNSTEIN, a citizen of the United States, residing at Chicago, in the county of Cook and State of Illinois, have invented a new and useful Improvement in Water-Heaters, of which the following is a specification.

My invention relates to an improvement in the class of apparatus known under the term "instantaneous water-heater," and designed especially for heating cold water as rapidly as it passes through the apparatus, thereby to afford convenient means where hot-water circulation is either not provided or is temporarily out of use for readily heating water for the bath, or for other purposes, by simply igniting the burner (gas, gasoline, oil, or the like) at the base of the heater and admitting to the latter the cold-water supply.

My improvement relates more particularly to the aforesaid class of the apparatus as represented by the Douglas water-heater, for which Letters Patent of the United States No. 345,416 were issued on the 13th day of July, 25 A. D. 1886.

The object of my invention is to provide a generally improved construction of device for producing the instantaneous heating of liquids, and with particular reference to the aforesaid Douglas heater my object is to simplify the construction, and more especially to provide a materially-larger heating-surface, thereby to effect more rapid and intense heating of the water in its passage through the apparatus.

In the accompanying drawings, Figure 1 is a view in elevation of my improved apparatus. Fig. 2 shows the same in vertical sectional elevation. Fig. 3 is a section taken at the line 3 3 in Fig. 2, and viewed in the direction of the arrows; and Fig. 4 is a plan view of the spraying device.

The apparatus comprises as its general construction an outer shell, preferably of circular shape in cross-section and cylindrical from its base part way up and tapering throughout the remainder of its extent, being open at its upper contracted end, and also, if desired, at its base; an inner tapering shell inside the outer shell and hermetically secured at its base thereto; another still shorter

tapering shell inside the last-named shell closed at its base to the latter and to the outermost shell, thus affording three conical chambers tapering all in the same direction; a 55 burner at the base of the apparatus, and a spraying device communicating through the outermost chamber with the liquid-supply pipe and suspended over the innermost shells, and adapted to direct the spray into the outermost and innermost said chambers.

A is the outer shell of sheet metal, cylindrical from its base upward throughout a part of its extent, and conical thence to its top, where it should be provided with a cap *r*, 65 terminating in a contracted opening or chimney *r'*.

B is a conical sheet-metal shell hermetically joined or sealed around its base or wider end to the inner surface of the shell A, sufficiently 70 high in the cylindrical lower portion thereof to afford in its base a chamber beneath the inner shells large enough to accommodate the heat-generating device, whether the latter be adapted for burning gas, oil, or other fuel. 75 Within the shell B is a narrower and shorter sheet-metal conical shell C, having a bottom *q*, through which it communicates by a T-coupling *p* with a pipe *o*, extending across the interior of the shell B, and leading at opposite ends through the latter, the shell C terminating at its upper end at or near the termination of the shell B, to which it may be secured for additional support near the upper end by bolts, as shown. The shells A and 80 B thus afford between them an upwardly-flaring chamber D, near the base of which a water-outlet spout *n* is provided. The shells B and C afford the upwardly-tapering chamber D' and the interior of the shell C affords 85 a downwardly-flaring chamber D'', communicating from its base with the chamber D at different points thereof through the pipe *o*.

E is the water-supply pipe, extending 90 through the shell A (beyond which it contains a valve *m*) into the chamber D and upward in the latter beyond the shells B and C, where it supports a spraying device F, adapted to spray the water into the chambers D and D'', and to that end comprising, as the preferred 95 construction, an annular tube *l*, provided with numerous small perforations in its under side

and supported from the head x , at which the spraying device is coupled to the pipe E, by tubular arms l' , and a tubular extension k , leading from the junction of the arms l' downward into the chamber D^2 , and provided therein with lateral minute perforations.

The apparatus as thus described may have employed with it for generating the required heat any suitable kind of furnace—such as a gas or an oil burner; hence I do not limit my improvement to the use of any particular kind or construction of device for supplying the heat.

The burner shown involves no features of novelty, being an old and well-known form of gasoline-burner for generating and burning gas from gasoline, and therefore need not be minutely described as to all of its details, being merely selected for illustration as one of the various kinds of burners I use, and particularly to show that gasoline may serve as the fuel for my purpose.

The burner illustrated involves an annular tube G, having perforations throughout its upper side and supported in the chamber afforded by the cylindrical portion of the shell A, and should be located, as shown, adjacent to the junction with the outer shell of the shell B. Below the tube G and communicating with it through a pipe h is the generator I for converting the gasoline into a vapor or gas, the supply of the latter through the tube h being controlled by a valve g and of the gasoline to the converter or generator by means of a pin-valve g' , and the supply of gasoline is provided in a reservoir H on the upper end of a pipe f , leading through the shell A near its base and having a branch f' , affording communication between it and the generator.

When a gasoline-burning appliance such as that described is employed, I provide, as usual, underneath it a "kindling-pan" e to receive the supply of the oil to be burned for initially heating to start the generation of gas in the generator I.

A drip-pan d should be located directly below the shell C to receive any moisture formed by condensation on the outside of the latter, and it communicates through a pipe d^2 with a similar drip-pan d' at the base of the apparatus, and into which also may be led through a spout c' moisture condensed on the inner surface of the shell B and intercepted by a trough c .

The operation is as follows: The burner being lighted, the flames from the numerous perforations in the ring G and the heat from the flames strike the inner surface of the shell B, the outer surface and base of the shell C, and pass upward through the chamber D' , rapidly and intensely heating the surfaces with which the heat comes into contact. The flow of water is then admitted through the pipe E, and emerges in a fine spray from the perforations in the parts l and k of the spraying device F, respectively,

against the outer surface of the shell B and inner surface of the shell C, absorbing heat from those surfaces as it flows down them on the shell B into the channel at its base formed by the junction thereof with the outer shell and on the shell C to its base q , whence it passes through the pipe o into the chamber D , mixing with the contents thereof, which are permitted to escape through the spout n .

What I claim as new, and desire to secure by Letters Patent, is—

1. In a water-heater, the combination of an outer shell A, an inner shell C, closed at its base to the furnace, and an intermediate shell B, sealed at its base to the shell A, chambers D, D' , and D^2 , afforded by the said shells, a pipe o , connecting the chambers D and D^2 , a spraying device suspended in the shell A to direct its spray into the chambers D and D^2 , and a furnace in the base of the heater, communicating with the chamber D' , substantially as and for the purpose set forth. 90

2. In a water-heater, the combination of an outer shell A, an inner shell C, closed at its base to the furnace, and an intermediate shell B, sealed at its base to the shell A, chambers D' and D^2 , intercommunicating near their bases, and a chamber D, afforded by the said shells, a pipe o , connecting the chambers D and D^2 , a spraying device suspended in the shell A to direct its spray into the chambers D and D^2 , and a furnace in the base of the heater, communicating with the chamber D' , substantially as and for the purpose set forth. 95

3. In a water-heater, the combination of an outer shell A, an inner shell C, having a base q , and an intermediate shell B, sealed at its base to the shell A, chambers D, D' , and D^2 , afforded by the said shells, a pipe o , communicating with the chamber D^2 through the base q and leading at opposite ends through the shell B into the chamber D' , a spraying device suspended in the shell A to direct its spray into the chambers D and D^2 , and a furnace in the base of the heater, communicating with the chamber D' , substantially as and for the purpose set forth. 105

4. In a water-heater, the combination of an outer shell A, an inner shell C, closed at its base to the furnace, and an intermediate shell B, sealed at its base to the shell A, chambers D, D' , and D^2 , afforded by the said shells, a pipe o , connecting the chambers D and D^2 , a spraying device F, having a perforated tube l and a perforated tubular extension k , the spraying device being suspended to communicate with the water-supply, with its tube l leading into the chamber D and its extension k leading into the chamber D^2 , and a furnace in the base of the heater, communicating with the chamber D' , substantially as and for the purpose set forth. 115

5. In a water-heater, the combination of an outer shell A, an inner shell C, having a base q , and an intermediate shell B, sealed at its base to the shell A, chambers D, D' , and D^2 , 125

afforded by the said shells, a pipe *o*, communicating with the chamber *D*² through the base *q* and leading at opposite ends through the shell *B* into the chamber *D*, a water-conveying pipe *E*, passing upward through the chamber *D* beyond the chambers *D'* and *D*², a spraying device *F*, suspended from the pipe *E* to direct its spray into the chambers *D'* and

*D*², and a furnace in the base of the heater, communicating with the chamber *D'*, substantially as and for the purpose set forth.

SAMUEL BERNSTEIN.
